UNITED STATES PATENT OFFICE.

FELICE RIZZO, OF SCHENECTADY, NEW YORK.

SIGNAL TRANSMITTER.

Application filed February 27, 1925. Serial No. 12,012.

The present invention relates to improvements in electric signalling systems, and has for its principal object to provide an improved transmitter which will close an operating circuit and open said circuit during one cycle of operation.

Other objects and advantages of this invention will become apparent during the course of the following description.

In the accompanying drawings, forming a part of this specification, and in which like numerals designate like parts throughout the same:

Figure 1 is a front elevation of the cabinet, showing the switch mechanism and the operating means therefor mounted thereon.

Figure 2 is a sectional view through the cabinet, showing the motor supported therein and the speed reducing gear frame associated therewith.

Figure 3 is a section taken at right angles to Figure 2, showing the motor and the gear train therein, the stationary contacts arranged on the outer face of the front of the cabinet, the movable contacts cooperating therewith, and the switch throwing arm.

Fig. 4 is a rear elevation of the front face of the cabinet, showing the annular series of stationary contacts supported thereon and the wiring therefor.

Figure 5 is a diagrammatic view illustrating a wiring arrangement of the system.

In the drawings, wherein for the purpose of illustration is shown the preferred embodiment of my invention, the numeral 1 designates a cabinet or the like, which is located in any convenient place, in a house or building. Supported within the cabinet 1 on a suitable bracket or stand 2 provided therefor is a portable electric motor 3, the same being of any conventional construction. The drive shaft of the motor is indicated at 4, and carried by the outer end thereof is the fiber gear 5, the purpose of which will be presently described.

A driven shaft 6 is journaled transversely in a suitable frame 7 provided therefor, the latter being supported within the cabinet 1 adjacent the front face thereof. The outer end of the driven shaft 6 extends through the front face of the cabinet, and is externally threaded, as illustrated more clearly in Figure 3 of the drawings. A relatively large gear 8 is carried by the transversely extending driven shaft 6 and

is arranged within the frame 7, the gear 8 being driven by a suitable train of gearing, designated generally by the numeral 9 which in turn is operated by the drive gear or pinion 5, carried by the outer end of the drive shaft 4. As this feature is of the usual construction, it is not thought necessary to further go into detail relative to the same, the purpose thereof being to reduce the speed of rotation of the driven shaft, as is obvious from the construction illustrated in the drawing.

Arranged on the outer face of the front side of the cabinet 1 in predetermined relation, are the snap throw switches 10 and 11 respectively, the same being of the conventional construction. Also arranged on the front side of the cabinet 1 is the annular series of spaced stationary contacts 12, the same extending through the front side of the cabinet, and arranged around the driven shaft 6.

Cooperating with the stationary contacts 12 is the movable contact 13, the same being in the form of a narrow strip of metal, which is supported at its inner end on the outer end of the transversely extending driven shaft 6. The outer end of the narrow strip of metal forming the movable contact 13 is curved, transversely, as well as longitudinally, so as to permit the convex face of the outer end of the movable contact 13 to be in engagement with the outer faces or heads of the stationary contacts 12 as the movable contact rotates simultaneously with the driven shaft. Adapted for simultaneous actuation with the movable contact 13 is the elongated arm 14, the same being secured at its inner end on the outer end of the driven shaft 6 by suitable nuts 15, a suitable washer 16 being placed on the driven shaft. A cotter pin or the like, shown at 17, extends through a suitable opening provided therefor in the outer end of the driven shaft, to prevent the accidental displacement of the fastening nuts therefrom so that the movable contact 13 and the arm 14 will at all times be secured on the end of the driven shaft. The outer end of the arm 14 extends beyond the annular series of spaced stationary contacts 12 and is adapted to cooperate with the snap throw switches 10 and 11.

In order to clearly illustrate the operation of the transmitter, I have shown a simple electric wiring diagram in Fig. 5.

When the switch arms shown at 10, 11 are disposed in the position shown and the switch 21 is closed, current will flow from the battery 18 through wires K, switch arm 10, contact 28, wire E and motor 3, and return through switch 21, wire J, wire H to battery. The operation of the motor, as previously explained, causes arms 14 to swing in a clockwise direction to engage switch arm 11 and swing it from contact 22 to contact 27 so that the current in the motor circuit may return to the battery through wire A, contact 27, switch arm 11, wire B and wire H even though the switch 21 is subsequently open. At the same time, current from the battery 18 may flow through wire J, wire 24' to energize the bell 25' returning to the battery through contact 27, switch arm 11, wire D and wire A to the battery. As the arm 14 continues to swing, the contact 13 engages those contacts 12 engaged by the wire L. The contact 13 is engaged by wire M, and of course, swings with the arm 14. The wires L and M are engaged with the switch 20 associated with wires leading to a suitable signaling apparatus (not shown) which is located in a fire engine house or station. The further swinging of the arm 14 brings it into engagement with the switch arm 10 so as to move this switch arm 10 from contact 28 to contact 24, thus breaking the motor circuit, but not breaking the bell circuit. To again operate the transmitter, it is apparent that the va-

rious switches must be manually reset to the 35 position shown in Fig. 5.

While I have shown the preferred embodiment of my invention, it is to be understood that various changes in the size, shape and arrangement of parts may be resorted to, if desired, without departing from the spirit of the invention or the scope of the appended claim.

I claim:

A transmitter of the class described including, in combination, a casing, an annular series of spaced stationary contacts arranged on one wall of the casing, a shaft journaled through said wall of the casing centrally of the series of contacts, a motor operatively associated with the shaft for imparting rotary motion thereto, a movable contact on said shaft associated with said stationary contacts to move thereover, a switch mounted on said wall of the casing outside of the annular series of contacts, and including a movable element and a stationary element, said elements being in circuit with the motor, and an arm mounted on the shaft to move synchronously with the movable contact for engaging, when in a predetermined position, the movable element of the switch, so as to disengage the movable element from the stationary element for the purpose of breaking the motor circuit.

In testimony whereof I affix my signature.
FELICE RIZZO.
